UNITED STATES PATENT OFFICE.

THOMAS JAMES LITTLE, JR., OF WOODBURY, NEW JERSEY, ASSIGNOR TO WELSBACH LIGHT COMPANY, OF GLOUCESTER CITY, NEW JERSEY, A CORPORATION OF NEW JERSEY.

IGNITING ATTACHMENT FOR GAS-BURNERS.

1,087,125.

Specification of Letters Patent. Patented Feb. 17, 1914.

Application filed January 27, 1912. Serial No. 673,761.

To all whom it may concern:

Be it known that I, THOMAS J. LITTLE, Jr., a citizen of the United States, residing at Woodbury, Gloucester county, New Jersey, have invented a new and useful Igniting Attachment for Gas-Burners, of which the following is a full, clear, and exact description, reference being had to the accompanying drawings, forming part of this specification, in which—

Figure 1 is a front elevation of a gas burner with a portion of the shade broken away, and showing one form of my invention applied thereto; Fig. 2 is a view of the same partly in section and partly in side elevation; Fig. 3 is a sectional detail view of the lighting attachment; Fig. 4 is a plan view of the same; Fig. 5 is a view similar to Fig. 2 but showing a modification; Fig. 6 is a view similar to Fig. 1, but showing the modified attachment of Fig. 5; and Fig. 7 is a plan view of the modified attachment of Figs. 5 and 6.

My invention has relation to gas-lighting devices adapted for use in connection with gas lamps, gas stoves, and in fact, any type of gas burning appliance; and more particularly to that class of gas-lighting devices which employ a pyrophoric alloy which has the property of emitting very hot sparks when scratched by a hard substance. It has been found that pyrophoric alloys of this character are more or less affected by heated products of combustion, so that the efficiency and spark-emitting qualities of the alloy become impaired.

The object of my invention is to provide a lighting device which is preferably in the nature of an attachment which can be quickly and readily applied to the burner with which it is to be used; and which can be moved from its lighting position to a normal position of rest, where it is not exposed to the flame or hot products of combustion.

Referring first to that form of my invention shown in Figs. 1 to 4, inclusive, the numeral 2 designates the body of a gas burner of the inverted incandescent type; 3 the shade holding ring; 4 the shade or globe; and 5 the mantle. 6 is the usual gas supply pipe, provided with the controlling valve 7. The body portion 2 of the burner is provided with the usual ventilating openings 8; and I utilize one of these openings

through which the lighting sparks produced by the operation of the lighting device are directed.

My invention may be permanently attached to the lamp or other burner with which it is to be used; but I preferably form it in the nature of an attachment which can be readily applied to existing lamps.

9 is a plate or bracket having the bent lips 9^a, which are adapted to engage the rim portion 3^a at the upper end of the gallery portion of the burner. The plate or bracket also carries a clamping screw 10, which engages the gallery portion of the burner in the manner shown in Fig. 2 to secure the attachment in place. Rigidly secured to the plate 9 is a sleeve 11, which extends obliquely downward and outward, and within which is arranged to slide a longer sleeve 11^a having clutch recesses or projections 12 at its lower end. Secured to the upper end of the sleeve 11^a is an abrading wheel 13, mounted within the guard frame 14, and which has a serrated or roughened periphery adapted to be rotated in contact with the piece of pyrophoric alloy 14^a. This piece of alloy is slidably mounted in a suitable guide groove in a holder 15, attached to the sleeve 11^a, and is pressed against the roughened periphery of the wheel by a suitable spring 16.

17 is a rod which extends loosely through the sleeve 11^a, and through the wheel 13, its upper projecting end portion having the two separated flanges or collars 18, and which slidably engages an eye 19 on an actuating rod 20 connected to the stem 21 of the gas-controlling valve 7.

22 is an actuating member, which is connected to the lower end of the rod 17 by a flexible joint 23.

24 is a spring holding device straddling the guard frame 14, and having arms which are adapted to engage the groove 25 in the rod 17, for the purpose presently described.

Extending upwardly from the plate 9 is a projection 9^b which is engaged by the holder 15 and a finger 15^a extending from the holder 15.

The operation is as follows:—When it is desired to light the lamp, the ring 26 at the lower end of the actuating member 22 is grasped, and said member is pushed upwardly as far as it will go. This upward movement brings the lower flange or collar 11^b

18 on the rod 17 into engagement with the eye 19 of the rod 20, and thereby actuates the gas valve to turn on the gas. This movement also brings a pin or pins 27 on the rod 17 into engagement with the clutch projections 12 on the sleeve 11^a, and raises the abrading wheel and the pyrophoric alloy from the position shown in Figs. 1 and 3 into the position shown in Fig. 2. The member 22 is then turned or twisted, the engagement of the pins 27 with the clutch projections 12 causing the rotation of the sleeve 11 and thereby of the abrading wheel 13 to produce the sparks which are directed through the adjacent opening 8 into the interior of the burner. Upon releasing the ring 26, the holder 15 and rod 17 drop by gravity to the position shown in Figs. 1 and 3, so that the alloy and abrading wheel are out of the path of the heated products. The arms of the spring holding device retain the rod 17 from falling by gravity with relation to the holder 15 and thereby prevent the valve 7 from being closed when the parts move downwardly; it being understood that the space between the flanges or collars 18 is equal to the movement of the holder 15. To extinguish the burner the ring is grasped and the member 22 pulled downwardly until the upper flange or collar 18 engages the eye 19 to thereby actuate the rod 20 and close the gas supply valve.

In Figs. 5, 6 and 7 I have shown a somewhat simpler form of my invention. In the form shown in these figures, the lighting device is carried by a plate or bracket 28, which is generally similar to the plate or bracket 9 before described, and is designed to be detachably secured to the burner in a similar manner. This plate or bracket is provided with a guide member 29 having guides for the oblique rod 30, to the upper end portion of which is rigidly secured the abrading wheel 31 adapted to be rotated in contact with the piece 32 of pyrophoric alloy which is held in a holder 33 similar to the holder before described. The wheel 31 is embraced by a strap 34, which has a guide projection 35 engaging the guide arm 36 on the plate or bracket 28. In the device shown in these figures, there is no connection between the lighting device and the gas supply valve, the latter being separately actuated in the usual manner. In the operation of this form of my invention, the abrading wheel and alloy are normally in the lower position shown in Fig. 6; and when it is desired to light the lamp, the rod 30 is pushed upwardly to bring these parts into the position shown in Fig. 5. The rod 30 is then rotated to produce the spark; and as soon as the rod is released the parts fall by gravity in the position shown in Fig. 6.

The advantages of my invention will be

readily apparent, since it provides a simple attachment capable of being readily applied to existing lamps; which is conveniently operated; and which, after it has been operated, falls by gravity into a position in which the abrading wheel and alloy are removed from the injurious effects of the heated products of the burner.

It will be obvious that my invention is susceptible of various changes in the details of construction and arrangement of the several parts, such as the exact manner of its attachment to the burner and of the details of construction.

I claim:—

1. The combination with a gas burner casing having a lighting opening therethrough, of an igniter for the burner exterior of the casing, comprising a piece of pyrophoric material and an abrader arranged to be moved into alignment with said opening, a movable carrier for the material and abrader, and actuating connections between the carrier and the gas supply valve for the burner for actuating the valve and moving the carrier together with the abrader in one direction; substantially as described.

2. A lighting attachment for gas burners, comprising a rotary and reciprocating sleeve member having an abrader attached thereto, and also carrying a piece of pyrophoric material in contact with the abrader, a rod or shaft movable longitudinally through the sleeve member and free to rotate therein when the attachment is in its inoperative position, and means for connecting the sleeve member and the rod to each other after a preliminary endwise movement of the rod to rotate said sleeve when the rod is rotated; substantially as described.

3. The combination with a gas burner having a lighting opening, of a support connected to the burner frame, a sleeve mounted on said support and having an abrading device, said sleeve member being capable of both a rotary and endwise movement, a rod extending through the sleeve member and adapted to be connected therewith in one position of the rod to rotate the sleeve when the rod is rotated, a gas supply valve for the burner, and a connection operated by said rod for opening and closing said valve; substantially as described.

4. A lighting attachment for gas burners, comprising a rotary and reciprocating sleeve member having an abrader attached thereto, and also carrying a piece of pyrophoric material in contact with the abrader, a rod movable through said sleeve member and free to rotate therein when the attachment is in its inoperative position, and a clutch device for connecting the sleeve member and the rod to each other to move the sleeve upwardly after the rod has been moved through the sleeve a predetermined distance,

said clutch being arranged to rotate the sleeve when the rod is rotated when the attachment is in its operative position; substantially as described.

- 5 5. A lighting attachment for gas burners, comprising a sleeve member having an abrader attached thereto, and also carrying a piece of pyrophoric material in contact with the abrader, a rod movable through the 10 sleeve member, means for connecting the sleeve member and the rod to each other after a preliminary endwise movement of the rod, a gas supply valve for the burner, and projections on the rod for actuating 15 the gas supply valve when said rod is shifted longitudinally; substantially as described.

6. An igniting attachment for gas burners, comprising a plate or bracket, a 20 clamping device for attaching the same to a burner frame, a bearing member on said bracket, and a pyrophoric sparking device having an actuating stem arranged to reciprocate and rotate in said bearing; substantially as described.

7. An igniting attachment for gas burners, comprising a plate or bracket, a screw clamping device for removably securing the same to a burner frame, a guiding 30 projection on the plate or bracket, a bearing member on said bracket, and a pyrophoric sparking device having an actuating stem arranged to reciprocate and rotate in said bearing, said sparking device being guided 35 by the guiding projection on the bracket; substantially as described.

8. A supporting member for a pyrophoric spark producing device, comprising a plate having a screw clamp, a sleeve rotatably 40 mounted in said plate, a rod or stem slid-

ably and rotatably mounted in said sleeve means for connecting the sleeve and rod after the rod has been moved upwardly a predetermined distance, and an abrader mounted on said sleeve and arranged to be 45 rotated thereby; substantially as described.

9. The combination with a gas burner casing having a lighting opening therethrough, of an igniter for the burner comprising a piece of pyrophoric material and an abrader, 50 a reciprocating carrier for the material and abrader, an actuator slidably and rotatably mounted in the carrier and connections on the actuator for rotating the abrader, the actuator being arranged to move the carrier 55 into alignment with a lighting opening and to rotate the abrader; substantially as described.

10. The combination with a gas burner casing having a lighting opening therethrough, of an igniter for the burner comprising a piece of pyrophoric material and an abrader, 60 a carrier for the material and abrader, an actuator slidably mounted in the carrier and connections on the actuator 65 for rotating the abrader, the actuator being arranged to move the carrier into alignment with a lighting opening and to rotate the abrader, there being a groove in the carrier for the pyrophoric material, and a spring 70 connected to the carrier and in engagement with the pyrophoric material for holding it in engagement with the abrader; substantially as described.

In testimony whereof, I have hereunto set 75 my hand.
